UNITED STATES PATENT OFFICE.

LOUIS L. MARTIN, OF TORONTO, ONTARIO, CANADA.

DOME-FASTENER.

1,261,836.

Specification of Letters Patent. Patented Apr. 9, 1918.

Application filed May 23, 1917. Serial No. 170,380.

To all whom it may concern:

Be it known that I, LOUIS L. MARTIN, a subject of the King of Great Britain, and resident of the city of Toronto, county of York, Province of Ontario, in the Dominion of Canada, have invented certain new and useful Improvements in Dome-Fasteners, as described in the following specification and illustrated in the accompanying drawings,

10 that form part of the same.

The principal objects of the present invention are, to eliminate the difficulties, inconveniences, and annoyances due to the accidental unfastening of this class of device and to devise a form of fastener which will lock absolutely secure against accidental disengagement, but which may be fastened or unfastened very easily without damaging the fabric to which it is secured 20 thereby obviating the tearing of garments made of fine fabrics.

A still further object is to devise a form of fastener which may be made with uniformity in extremely small sizes and in 25 which the number of parts and mechanical operations are reduced to the minimum, consequently minimizing the cost of manufacture.

The principal features of the invention 30 consist in the novel formation of a pair of engaging plate members, whereby a headed projection upon one member is held with the flange of the head in positive locking engagement with the edges of a slot formed 35 in the other member by a projecting portion of one member spring engaging a projecting portion of the other member and whereby the headed member is directed into and out of engaging contact with the slot- 40 ted member by an inclined surface arranged at one end of the slot.

In the accompanying drawings, Figure 1 is an enlarged transverse sectional view, upon an enlarged scale, of a fastener constructed in accordance with this invention, the parts being shown in the position of being placed together.

Fig. 2 is a sectional view similar to Fig. 1 showing the parts in the locked position.

50 Fig. 3 is a plan view, showing the members in the position illustrated in Fig. 1.

Fig. 4 is a top plan view of the headed member.

Fig. 5 is a part sectional, part elevational 55 view through the line *a—b* of Fig. 2.

Corresponding reference numerals refer

to corresponding parts in the various figures.

Numerous forms of dome fasteners have been placed on the market from time to 60 time and in those forms which are at present obtainable the element of securing the two members together, is a spring member engaging the dome head. This spring holding element is very unsatisfactory, in 65 that in order that the spring may be sufficiently strong to retain the garment secured it is over strong to allow of ready separation and as this class of fastener is used very extensively on light flimsy materials 70 the tearing of the fabrics frequently results.

It is found in practice that such spring holding fasteners vary considerably in their degree of strength, consequently one will be very stiff to fasten and unfasten and another will come apart with a very slight pull upon it and as this class of device is made in very small sizes it is impossible to obtain any degree of accuracy in the making and setting of the spring.

The present invention eliminates all these difficulties and provides a fastener which will be simpler and stronger and also cheaper to manufacture than the spring holding kind. The dome member 1 is preferably formed of circular shape from thin sheet metal, having the dome head 2 centrally arranged. Surrounding the head 2 is an annular rib 3 which is spun or pressed up in the metal coincident with or successively following the formation of the head. The diameter of the neck 4 is considerably smaller than the greatest diameter of the head and a circular shoulder is thus formed under the head.

The mating member 5, which is preferably stamped up in circular form of corresponding size with the member 1, is provided with an upwardly extending canopy portion 6 which is adapted to receive the head 2 of the member 1. This canopy is arched transversely to correspond with the shape of the head, shown particularly in Fig. 5, and at the open side 7 the plate 5 is formed with a slot or notch 9 arranged in 100 central alinement with the canopy and adapted to receive the neck 4 of the dome, so that when the dome is pressed into position with the neck engaging the end of the slot or notch 9, the metal of the plate 105 110 will engage the underside of the head, thus forming a secure and positive engagement.

The plate 5 is formed with one or more detents 10 pressed in the metal which are adapted to engage the annular rib 3. The material of the plate is very thin and 5 springs readily so that these detents 10 will readily slip over the rib when the members are brought into engagement and pressed transversely and when so engaged the members are securely locked from accidental 10 separation.

The plate 5 is preferably split at the points 11 where the canopy portion 6 joins the main body of the plate, so as to add to the springing quality. The slotted plate is 15 provided with a suitable mark 12, which is used as an indicator to insure the member being properly placed upon the garment so as to interlock with the headed member. The canopy portion is so arranged that when 20 the head is inserted from the under side it is guided by the inclined end surface 13 to bring the neck portion into the notch or slot 9 and the spring engagement of the detents 10 with the rib 3 holds it in place. 25 When in this position the two members cannot be separated by an outward pull but are required to be moved longitudinally in a direction in reverse to the pull and as the 30 pull of the garment will be in the direction to hold the dome at the end of the slot in locking engagement the garment can not be accidentally parted.

When the fastener is to be disconnected the members are pressed longitudinally so as 35 to spring the detents over the engaging rib 3 and move the head out of the slot or notch 9. The curved surface 13 at the back end of the canopy directs the head outwardly so that the members separate 40 freely, there being no projecting portion upon which the head may catch in its removal. This is a very important feature of the invention and insures a smooth and easy 45 operation in both fastening and releasing operations.

What I claim as my invention is:—

1. A dome fastener comprising a plate of thin sheet metal having a headed projection and an annular rib surrounding the base of 50 said head, a plate of thin sheet metal having a slot adapted to receive the head, said slot having a reduced portion adapted to receive the neck of said headed projection and to engage the underside of the head, 55 the slotted plate having detents adapted

to engage said annular rib to retain the headed projection in locking engagement.

2. A dome fastener comprising a plate of thin sheet metal having a headed projection and an annular rib surrounding the base 60 of said head, a plate of thin sheet metal having a slot adapted to receive the head, said slot having a reduced portion adapted to receive the neck of said headed projection and to engage the underside of the head, the 65 slotted plate having spring detents arranged adjacent to the ends of the slot and adapted to engage said annular rib to retain the neck of the slotted projection in locking engagement. 70

3. A dome fastener comprising a plate of thin sheet metal having a headed projection, a plate of thin sheet metal having a slot formed with a reduced portion adapted to receive the neck of the head and to engage 75 the underside thereof, said slot having an enlarged end formed by an indent in the metal which forms a concaved surface adapted to direct the head into and out of the slot, and spring detents adapted to engage the headed plate to retain the headed projection in locking contact. 80

4. A dome fastener comprising a plate of thin sheet metal having a headed projection and an annular rib surrounding the base of 85 said head, a plate of thin sheet metal having a recess adapted to receive the head, said recess being open at one side and the plate having a slot arranged centrally of said opening and adapted to receive the neck 90 of said head and to engage the underside thereof, the recessed plate having detents adapted to engage said annular rib in spring engagement to retain the head in locking engagement. 95

5. A dome fastener comprising a plate of thin sheet metal having a headed projection, a plate of thin sheet metal having a recess adapted to receive the head and presenting a beveled surface at one side and at the opposite side having an opening, said plate having a slot centrally arranged of said opening in said recess adapted to receive the neck of said headed projection and to engage the underside of the head, said recessed plate having detents adapted to engage the headed plate to retain the head in locking engagement. 100 105
